LOCOMOTIVE JOURNAL OILER

Joseph P. Savage, Columbus, Nebr.

Application June 6, 1936, Serial No. 83,986

10 Claims. (Cl. 308—91)

The present invention relates to journal box lubricators or oilers and the primary object of the invention is to provide an improved locomotive journal oiler which will assure constant lubrication of the journal at all times.

A further object of the invention is to provide an improved driving box cellar which may readily be substituted for the present types of cellars, and one wherein loss of oil is prevented.

10 A further object resides in the improved means for conveying the oil to the journal and spreading the oil therealong for proper lubrication.

A further object of the invention resides in the provision of means for properly lubricating the 15 oil feeding means employed for conveying the oil to the journal.

A further object is to provide an improved journal oiler which while not limited to such use, is especially well adapted for use in connection with 20 locomotive driving boxes.

A still further object is to provide a driving box cellar which may be readily filled with oil without removal from the box, and also embodying means for gauging the amount of oil in the 25 cellar.

A still further object resides in the provision of a self-locking keeper bolt to removably retain the journal oiler in the box.

Other objects and advantages of the invention 30 will be apparent from the following detailed description, taken in connection with the accompanying drawing, forming a part of this specification and in which drawing:—

Figure 1 is a vertical transverse section thru 35 the journal oiler shown applied and looking at the inner end of the driving box with which the oiler is associated.

Figure 2 is a vertical longitudinal section thru 40 the oiler shown applied to the driving box.

Figure 3 is an end view of the journal oiler or cellar and showing portions broken away for illustrating certain details of construction.

Figure 4 is a top plan view of the oil feeder unit shown detached from the lubricator.

Figure 5 is a fragmentary sectional view of a 45 portion of the lubricating means shown removed from the oil container.

Figure 6 is an enlarged detail view of one end portion of a cellar or keeper bolt.

50 In the drawing and wherein like reference characters designate corresponding parts thruout the several views, the letter A designates a driving box of conventional construction provided with the improved journal oiler or cellar B. The letter C designates a driving axle journal mounted

in the box A and on the outer ends of which the driving wheels are mounted as at D.

The driving box A is of usual construction embodying the depending side arms 5 between the upper ends of which is mounted the bearing 6 5 retained in place by the holding plate 7 disposed at the inner end of the box.

Referring now to the construction of the oiler or cellar B, the same is adapted to removably fit between the arms 5 beneath the journal C and embodies an oil container or cellar proper 8 of box-like formation providing vertical side walls 9, end walls 10 and a bottom wall 11. The end walls 10 have their upper edges of semi-circular shape as shown in Figure 3 for receiving the 15 journal C. Depending from each corner portion of the bottom wall 11 is an apertured lug 12 and these lugs are adapted to receive cellar or keeper bolts E for removably supporting the oiler between the arms 5.

Arranged within the container 8 is a lubricating means for conveying oil to the journal C and this means embodies an open rectangular-shaped frame member 13 having side rails 14 and end rails 15. Secured along its lower edge to the 20 outer side of each side rail 14 is a wiper plate 16 formed of spring material and which has a normal tendency to spring inwardly at its upper portions as shown in Figure 5. These wiper plates 16 extend substantially thruout the length of the side 25 rails 14 and have secured along their upper edges and at their inner or confronting sides, strips of felt or the like 17 which are normally urged into wiping contact with the journal C.

Adapted to be removably supported in the open 30 frame member 13 is an oil feeder or lubricator unit F for conveying oil disposed in the container 8 to the journal C. This unit F comprises a supporting shaft 18 which is adapted to be secured at its ends to the end rails 15 as by screws or the like 19 passed thru openings 20 in the ends 35 of the shaft. Slidably fitted on the shaft 18 is a substantially semi-circular shaped dip cup 21 having bushings or sleeves 22 extending from opposite sides thereof which receive the shaft 18. Extending thru the shaft 18 and the sleeves 22 are cotter pins 23 which act to retain the cup 40 and sleeve assembly against rotation on the shaft so that when the shaft is secured by the screws 19 to the end rails 15, the open side of the dip cup 21 will be retained uppermost as shown in 45 Figure 1.

Freely rotatable upon the shaft 18 within the dip cup 21 is an oil feeding wheel 24 adapted to have rolling contact with the journal C, and this 50 55

oiling wheel is preferably provided at its periphery with a rounded groove forming spaced annular surfaces for contacting the journal. The wheel 24 rotates in oil within the cup 21, the cup having an opening 25 in its bottom for admitting oil disposed in the container 8.

Provided at the upper edge and at one end of the cup 21 is a drip catch pan 26 for catching excess oil scraped from the journal in a manner 10 to be later described. This drip pan 26 as will be observed has its bottom wall downwardly inclined toward the cup 21 and has its side walls converging towards the cup whereby the collected oil feeds toward the cup. The wall 27 of the drip 15 pan preferably extends above the side walls of the pan and forms a shield plate for directing oil into the pan. Communicating with opposite sides of the drip pan, at the low point of the pan, are two oil delivery tubes 28 which extend along opposite sides of the cup 21 for delivering oil collected in the pan to the bearing of the oil feeding wheel 24. These tubes 28 may open thru the sides of the cup 21 directly above the shaft 18. Owing to the high speed at which the oiling 20 wheel 24 may revolve at certain times, the oil is thrown by centrifugal action to the periphery of the wheel and away from its bearing. The delivery tubes 28 will insure lubrication of the oiling wheel shaft and allow for a lower oil level 25 being maintained in the oil container 8.

Acting between each corner portion of the open frame member 13 and the bottom wall 11 of the oil container 8, is a coil spring 29 which normally urges the frame member upwardly and the oiling 30 wheel 24 into rolling contact with the journal C.

Arranged at each end of the oil container 8, is an inner end wall or plate 30 disposed inwardly of the end walls 10, and an outer end wall or plate 31 disposed outwardly of the end walls 10 40 whereby these plates 30 and 31 have vertical telescoping relation to the end walls 10. The upper edges of the plates 30 and 31 are of semi-circular shape as shown in Figure 3 for receiving the journal C. Secured to the inner side of each inner end plate 30 about the upper edge thereof is a felt strip 32, while secured between the plates 30 and 31 about the upper edges thereof is a second felt strip 33. These felt strips 32 and 33 are secured to the plates by rivets or the like 34 which 45 also serve as means for securing the plates 30 and 31 together at their arcuate upper edges. As will be observed in Figure 2, the felt strips 33 act as spacers for the end plates 30 and 31 so that the end walls 10 of the oil container may extend 50 between the plates. The inner end plates 30 are provided adjacent each end with vertical slots 35 which receive pins 36 projecting from the end rails 15 whereby the end plates may move vertically with respect to the frame 13. Secured to 55 the inner side of each inner end plate 30, adjacent to the side edges thereof, are angle brackets 37 against the under sides of which coil springs 38 act in a manner to normally urge the connected end plates 30 and 31 upwardly and the felt strips 32 and 33 into contact with the journal C. The lower ends of these coil springs 38 bear upon the end rails 15 of the frame member 13.

Pivoted mounted within the frame member 13 is a pair of U-shaped scrapers 40 each embodying 70 a scraper bar 41 extending parallel to the oiling wheel shaft 18 and arms 42 pivotally mounted at their lower ends as at 43 to the end rails 15. The lower ends of the arms 42 below the pivots 43, are provided with offsets 44 which are offset towards the side rails 14 and act as stops for limit-

ing swinging movement of the scrapers toward one another. Connecting the arms 42 at each end of the scrapers 40 is a coil spring 45 and these springs act to retain the scraper bars 41 in contact with the journal C. When the frame member 13 is removed from the oil container 8, the offsets 44 will contact the side rails 14 as shown in Figure 5 and limit inward swinging of the scrapers by the springs 45. The scrapers 40 not only act to prevent excess feeding of oil to the journal, but also as means for spreading the oil 10 along the journal.

The oil container 8 is provided at one end wall 10 with a filler spout 46 in which is disposed a float gauge 47 for gauging the oil level in the 15 container 8. As will be observed in Figure 2, the combined oil gauge and filler is disposed at the inner end of the driving box.

Referring now to the construction of the cellar or keeper bolts E, the same are of a self-locking 20 type and serve to removably secure the oiler or cellar B in position in the driving box A. The bolt E embodies a shank 48 having a crank 49 at one end and having its opposite end screw threaded as at 50. The threaded end 50 is longitudinally 25 slotted as at 51 and pivotally mounted in this slot is a key 52 which, when the shank 48 is in a horizontal position, may swing by gravity to a vertical position transversely of the shank as shown in Figures 1 and 6. The key 52 when disposed longitudinally in the slot 51 lies inwardly of the screw threads 50, and one end of the key is formed at an angle for engaging the angular inner end of the slot 51 whereby the key may be retained longitudinally in the slot during placing and removal of the keeper bolt. The side 30 arms 5 of the driving box A are provided at their lower ends with lugs 5' which are apertured to align with the apertures in the lugs 12. The apertures in the lugs 5' of one side arm 5 is 40 preferably threaded for receiving the threaded end 50 of the keeper bolt. When the threaded end 50 projects so that the key 52 clears the lugs 5', the key will swing by gravity to the position shown in Figure 1 and thus retain the bolt in 45 position. As will also be observed in Figure 1, the crank 49 and the key 52 both hang downwardly when the bolt is in use.

With the container 8 filled with oil to the desired level, the oil will pass into the dip cup 50 21 thru the opening 25 where it will be picked up by the oiling wheel 24 and transferred from the periphery of the wheel to the journal C. With the journal rotating in the direction of the arrow shown in Figure 1, the surplus oil will be scraped 55 from the surface of the journal and allowed to drop into the drip catch pan 26 and from which this oil is delivered to the bearing of the oiling wheel thru the tubes 28. Since the reversed or backward travel of locomotives is limited to low 60 mileage, the drip catch pan need only be provided at one end of the dip cup for functioning during forward travel of the locomotive.

As will be observed, the lubricator unit F is of simple construction, and by removing the screws 65 19, the entire unit may be removed from the container. By removing the cotter pins 23 the shaft 18 and oiling wheel 24 may easily be removed from the bushings 22 and the dip cup 21 for examination or replacement of parts.

While the oiler has been shown and described 70 for use in connection with locomotive driving boxes, it will readily be seen that with slight modifications to the shape of the oil container 8, the oiler may be associated with engine truck boxes. 75

Changes in detail may be made to the form of invention herein shown and described, without departing from the spirit of the invention or the scope of the following claims.

5. I claim:

1. In a journal box lubricator, an oil cellar, a frame member vertically movable in the cellar embodying end and side rails, spring means normally urging the frame member upwardly in the

10 cellar, an oiling wheel supported in the end rails, yieldable wiper plates secured at their lower portions to the side rails and having a normal tendency to spring inwardly at their upper portions, retaining plates yieldably carried by the end portions of the frame member, a scraper pivoted on the frame member at each side of the oiling wheel, and spring means normally urging the scrapers toward one another at their upper portions.

20. 2. In a journal box lubricator, an oil cellar, an open frame member vertically movable in the cellar embodying end and side rails, spring means normally urging the frame member upwardly, an oiling wheel supported in the end rails, yieldable wiper plates secured to the side rails and each having a felt strip along its upper inner side, a pair of connected inner and outer end plates at each end of the frame member and provided with felt strips about their upper edges, and spring means yieldably supporting the end plates upon the frame member to permit relative vertical movement between the end plates and the frame member.

30. 3. In a journal box lubricator, an oil cellar embodying end and side walls and a bottom wall, an open frame member in the cellar embodying end and side rails, spring means normally urging the frame member upwardly in the cellar, an oiling wheel supported in the end rails, a yieldable wiper plate secured at its lower portion to each side rail, a pair of connected inner and outer end retaining plates telescopically associated with each end wall of the oil cellar, and spring means yieldably supporting the retaining plates upon 45 said frame member.

40. 4. In a journal box lubricator, an oil cellar, an open frame member vertically movable in the cellar embodying end and side rails, an oiling wheel supported in the end rails, spring means normally urging the frame member upwardly in the cellar, a pair of U-shaped scrapers pivoted upon the end rails at opposite sides of the oiling wheel, a coil spring normally urging the scrapers toward one another at their upper portions, and 55 means limiting movement of the scrapers toward one another.

55. 5. In a journal box lubricator, an oil cellar,

an open frame member vertically movable in the cellar, a lubricator unit supported on the frame member embodying an oiling wheel and a supporting shaft therefor, spring means normally urging the frame member upwardly in the cellar, 5 a scraper pivoted on the frame member for yieldably engaging a journal, and means for lubricating the oiling wheel.

6. In a journal box lubricator, an oil cellar, an open frame vertically movable in the cellar 10 embodying end and side rails, spring means normally urging the frame upwardly in the cellar, a scraper pivoted on the frame, and an oil feeder unit embodying a shaft mounted at its ends in said end rails, a dip cup supported on the shaft, 15 an oiling wheel journaled on the shaft within the cup, a drip collector means for catching oil from the scraper, and means for conveying oil from the drip collector means to the journal for the oiling wheel.

20. 7. In a journal box lubricator, an oil cellar, an open frame vertically movable in the cellar embodying end and side rails, spring means normally urging the frame upwardly in the cellar, a scraper pivoted on the frame, embodying a 25 scraper bar, a shaft secured at its ends to said end rails, a dip cup secured to the shaft, an oiling wheel rotatable on the shaft within the dip cup, a drip catch pan on the cup and extending beneath said scraper bar, and oil tubes for conducting oil collected in the drip pan to the bearing surface of the oiling wheel.

30. 8. In a journal box lubricator, an oil cellar, an open frame in the cellar, and a lubricator unit detachably associated with the frame embodying 35 a dip cup, an oiling wheel journaled in the cup, and drip collector means for lubricating the oiling wheel journal.

35. 9. In a journal box lubricator, an oil feeder unit comprising a supporting shaft, a dip cup 40 thru which the shaft extends, a sleeve encircling the shaft at each side of the cup and rigid with the cup, means for securing the sleeves to the shaft, an oiling wheel rotatable on the shaft within the dip cup, a drip catch pan on the cup, 45 and oil tubes for conveying oil from the drip catch pan to the bearing for the oiling wheel.

40. 10. In a journal box lubricator, an oil cellar, a frame member vertically movable in the cellar, an oiling wheel supported in the frame member, 50 a combined oil gauge and filler at one end of the oil cellar, coil springs normally urging the frame member upwardly, scrapers pivotally carried by the frame member, yieldable wiper plates carried by the frame, and retaining plates yieldably supported upon the frame member.

JOSEPH P. SAVAGE.
